UNITED STATES PATENT OFFICE

2,608,307

DEVICE FOR VISUAL INSPECTION OF
METALLIC BALLS

Adolph J. Oborski, Chicago, Ill.

Application May 24, 1950, Serial No. 163,846

9 Claims. (Cl. 214—1)

1

The present application is a continuation in part of the application, Serial No. 130,003, filed November 29, 1949, now abandoned.

The present invention relates to a device for imparting to steel balls a rotary movement in order that the same may be subjected to a visual inspection for determining the perfection of the steel balls used for ball-bearing and the like.

Another object of the present invention is the provision of means for imparting to steel balls a rotary movement along a plurality of their axes so as to expose the entire peripheries of the balls to a visual inspection in order to determine whether or not the balls have any flaws or imperfections, so that imperfect balls may be discarded.

A further object of the present invention is the provision of a tray provided with a plurality of openings, into which a plurality of steel balls may be positioned, said tray co-acting with a traction support, such as a rubber pad, so that when the tray is placed in a contactual relation with a traction support and is shifted thereon, a rotary movement to the steel balls, which contact the traction support, may be imparted for the purpose of facilitating a visual inspection of the balls.

A still further object of the present invention is the provision of a tray provided with a plurality of openings, which, adjacent the upper face of the tray are of a diameter larger than their diameter adjacent the lower face of the tray, which openings from seats for steel balls, and which permit the steel balls to contact a traction support, such as a rubber pad, when the tray is laid thereon in contactual relation, and whereby the steel balls may be capable of rotary movement when the tray is shifted upon said traction support for the purpose of exposing the entire peripheries of the steel balls for facilitating a visual inspection thereof.

A still further object of the present invention is the provision of means, in association with a tray of a character hereinabove indicated, for filling all of the openings in the tray at a given time.

Another object of the present invention is the provision of a box having a stationary plate and a shiftable plate, each provided with a plurality of openings, the openings in the two plates being capable of coming into or out of register when the shiftable plate is shifted into one or another direction, so that the balls stored in the box may pass through the openings in the two plates when the same are in register, and whereby they may be deposited in the openings in the tray for simultaneously filling all of the openings in the tray.

2

Another object of the present invention is the provision of a guiding hopper in association with the said box, into which a quantity of balls may be poured and by means of which the balls may be guided for proper distribution in one or two layers over and above the upper, shiftable plate.

A still further object of the present invention is the provision of a storing hopper into which a comparatively larger quantity of balls may be deposited, with means associated therewith whereby a smaller, predetermined quantity of balls may be caused to flow into the said guiding hopper for shifting therefrom upon the said upper, shiftable plate.

Another object of the present invention is the provision of an inclined track connecting said guiding hopper with said storing hopper, whereby the balls due to gravity may roll from the latter into the former, with means associated with said track for regulating the quantity of balls rolling from said storing hopper into said guiding hopper at any given time.

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views:

Fig. 1 is a plan elevational view of the present device;

Fig. 2 is a side elevational view thereof;

Fig. 3 is a cross-sectional view, taken on line 3—3 of Fig. 1, illustrating a pair of perforated plates, with openings therein in register for permitting passage of steel balls therethrough to drop upon and fill a tray disposed therebelow;

Fig. 4 is a similar view with one plate shifted with relation to the other plate so as to bring the openings in the two plates out of register and thereby preventing passage of steel balls above the plates through the openings, preparatory to the withdrawal of the tray with steel balls thereon;

Fig. 5 is an enlarged, fragmentary, cross-sectional view through the tray;

Fig. 6 is a top elevational view of a guide of a modified construction for guiding the tray in its agitating movement;

Fig. 7 is a cross-sectional view on line 7—7 of Fig. 1;

Fig. 8 is a plan elevational view of the machine

with a storing hopper added thereto, with a track connecting said storing hopper with movable hopper, upon which track the balls are caused to roll from said storing hopper into said movable hopper, with means for regulating the quantity of balls rolling from the former into the latter; and

Fig. 9 is a side elevational view of the machine, with the cross-section of the said storing hopper and the track.

Referring in detail to the present drawings, there is shown therein table 10 supported upon legs 11. Supported by the lower ends of said legs 11 is ledge 12.

A substantially rectangular box, including rear wall 13, front wall 14 and a pair of side walls 15, is rigidly affixed to said table 10 by means of screws 16, passed through said table 10 and engaging said side walls 15. The walls of said box are rigidly interconnected by any suitable means. The upper end of said box is open, as is clearly seen in Figs. 3 and 4.

Hopper 17, in a spaced relation with the walls of said box, enters the said box through its open upper end, and is supported in a suspended relation by a pair of brackets 18 which are rigidly affixed to the upper ends of side walls 15 of said box.

Said rear wall 13, and side walls 15 are provided, adjacent their lower ends, and on the inner faces thereof, with a continuing groove 19 for reception therewithin of the marginal portions of stationary plate 20 and shiftable plate 21. Front wall 14 on line with said groove 19 is recessed, as at 22 through which said plates 20 and 21 may be shifted into their operative position within the box and within groove 19.

Stationary plate 20, by its front edge, remains flush with the outer face of front wall 14 when the remaining marginal edges thereof repose within groove 19. Shiftable plate 21, however, is narrower than said stationary plate 20, as is seen in Figs. 3 and 4, in order that the former may be capable of shifting transversely of rear wall 13 and front wall 14.

Said stationary plate 20 and said shiftable plate 21 are each provided with a plurality of round openings 23, slightly larger than the diameters of steel balls 24 to be passed through said openings 23 in both of said plates when said openings are in register, as is seen in Fig. 3. At the upper faces of said stationary and shiftable plates 20 and 21, and adjacent each opening 23, the body portions of said plates adjacent said openings are chamfered, as at 25, for facilitating rolling of balls 24 into said openings 23.

Rigidly affixed to the upper face of the rear marginal portion of said shiftable plate 21 is bar 26, accommodated within recess 27 made in the rear wall 13. Similar recess 28 is made in front wall 14, through which said bar 26 may be extended when said shiftable plate 21 is shifted in position within the box through opening 22 made in the said front wall 14.

Affixed to the outer face of one of said side walls 15 is post 29, the upper end of which is bifurcated for receiving therewithin lever 30, which is pivoted upon pin 31. The outer, front end of said lever has handle 32 attached thereto. The opposite end of said lever is bent, substantially at a right angle, and is directed downwardly, and is bifurcated for receiving therewithin in pivotal relation arm 33, the opposite end of which pivotally connects with bar 34, which is keyed to the end of rocker shaft 35. Said rocker shaft 35 is supported for rocking movement with-

in a pair of brackets 36, which are rigidly affixed to the outer face of said rear wall 13. Collars 37, rigidly affixed to said shaft 35, are in contact with said brackets 36 for preventing longitudinal shifting of said shaft 35.

Intermediately of said brackets 36, said shaft 35 has arm 38 keyed thereto, the lower end of said arm 38 being bifurcated for receiving therewithin the outer end of said bar 26. The end of said arm 38 carries pin 39 which is extended through slot 40 made in said bar 26, for providing a pivot for actuating said bar 26 and shift the same longitudinally into one or the opposite direction.

When lever 30 is raised, as seen in Fig. 2, arm 38 will remain in a substantially vertical position, as is seen in Figs. 2 and 3. In that position of arm 38 shiftable plate 21 by its rear marginal edge will remain within groove 19 in the rear wall 13, with openings 23 thereof in register with openings 23 in stationary plate 20, permitting passage of balls 24 through the two sets of said openings 23. When however said lever 30 is shifted into a downward direction, a rocking movement to shaft 35 will be imparted, through the medium of arm 38 and bar 34, for shifting the lower end of arm 38 towards the front wall 14 of said box. This operation brings openings 23 in shiftable plate 21 out of register with openings 23 in said stationary plate 20, as is clearly seen in Fig. 4. This operation does not permit balls 24 to pass through both sets of openings, although balls 24 may rest within openings 23 of said shiftable plate 21 during the shifting movement of said latter plate.

The said box is filled with balls 24 by dropping them therewith through hopper 17, so that the balls within the box rest upon said shiftable plate 21. Of course, the lowermost of said balls 24 will fill openings 23 in said shiftable plate 21, or will pass through openings 23 in said stationary plate 20, if both sets of openings 23 are in register. In order that balls 24 may not enter recess 28 plate 41, attached by means of screw 42 to the upper end of front wall 14, forms a skirt adjacent the inner end of said recess 28, thereby preventing any balls 24 within the box to enter said recess 28.

Said guiding hopper 17 by its lower end is in a spaced relation with said shiftable plate 21, the space therebetween corresponding at least to the diameter of single ball 24, but does not exceed double diameters of balls 24. By virtue of this arrangement, when hopper 17 is filled with balls 24 only the lowermost balls 24 in direct contact with shiftable plate 21 will be capable of spilling laterally of hopper 17. Were it otherwise, or were hopper 17 entirely eliminated, balls 24 within the box would constitute a heavy mass which would prevent plate 21 from shifting or balls 24 from filling openings 23. By virtue of the spaced relation of hopper 17 with plate 21 as well as by virtue of the spaced relation of the walls of hopper 17 with the walls of box defined by walls 13, 14 and 15, the lowermost layers of balls 24 above and upon plate 21 define a sufficiently loose mass which does not prevent balls 24 from filling openings 23 and does not prevent plate 21 from shifting when actuated by lever 30.

Co-acting with said plates 20 and 21 is tray 43, which is insertable through opening 22 in said front wall 14, and in its operative position is disposed below said stationary plate 20, as is seen in Figs. 3 and 4.

Said tray 43 is provided with a plurality of openings 44, which, on transverse cross-section through said tray 43 are of frusto-conical shape,

the upper ends of which are wider, and the lower ends of which are constricted, for providing seats for balls 24. Said openings 44 are of a diameter considerably smaller than the diameter of balls 24, so that barely a small portion of the hemisphere of ball 24 may be received within any one of said openings 44. However, said openings 44 are sufficiently wide so that when balls 24 are seated therewithin, a small peripheral portion of said balls are extended through tray 43. The body portion of tray 43 at its lower face, adjacent each opening 44 is chamfered as at 10 45. Said openings 44 in tray 43, when the latter remains in an operative position with relation to said stationary plate 20, are in alinement with openings 23 in said stationary plate 20, as is seen in Figs. 3 and 4. Tray 43 is further provided with a plurality of upwardly projecting lugs 46, which contact with the underface of said stationary plate 20, and maintain said tray 43 in a proper spaced relation from said stationary plate 20.

Affixed to the front edge of said tray 43, and at the upper face thereof, is angle member 47, of a thickness lesser than the height of lugs 46 so as not to interfere with the operation of the latter. The vertical portion of said angle member 47 contacts with the front face of said front wall 14 when tray 43 remains below stationary plate 20 in condition to receive balls 24. The vertical portion of said angle member 47 is considerably longer than the length of the said box, so that the ends of the vertical portion of said angle members 47, extend considerably beyond and laterally of said side walls 15, as is seen in Fig. 1.

Affixed to each end of said vertical portion of angle member 47, and at the rear face thereof, is block 48, from the lower end of which cylindrical roller 49 downwardly projects.

Cooperating with tray 43 is supporting plate 50, which has rigidly affixed to its lower face a cylindrical stud 51, entering sleeve 52. Said sleeve 52 enters through an opening made in table 10 and extends upwardly thereabove. Said sleeve 52 is integrally formed with plate 53, which is affixed to the underface of table 10 by means of a plurality of screws 54. Integrally formed with said stud 51, and downwardly depending therefrom, is a reduced cylindrical boss 55. Integrally formed with said boss 55 is rod 56, which downwardly extends through plate 51. Plate 57 rigidly connects with plate 53 by means of a plurality of screw bolts 58. Coil spring 59, encompassing rod 56 bears by its lower end against plate 57, and against stud 51 by its upper end. The reduced boss 55 in conjunction with said stud 51 provides a shoulder at said stud 51 against which said coil spring 59 bears and with which the same is in contact. The upper end of coil spring 59 remains in contact with the periphery of said boss 55 for maintaining said coil spring in position.

Collar 60, upwardly extending from plate 51, around which said coil spring 59 is set, provides the anchoring means for the lower end of said coil spring 59.

Rod 56 is connected by pin 61 to rod 62, the lower end of which is pivotally connected, as at 63, to extension 64 which projects from treadle 65, swivelled upon ledge 12 by means of hinge 66.

Coil spring 59, bearing against stud 51 causes plate 50 to remain in contact with tray 43 for the purpose of pressing lugs 46 against the underface of stationary plate 20. When an operator's

foot placed upon treadle 65 presses the latter, rod 62, with rod 56 and stud 51 is downwardly shifted, against the tension of spring 59 for downward shifting of plate 50 and tray 43, in order to bring the latter away from said stationary plate 20, as is indicated in dotted lines in Fig. 4.

Placed upon table 10, forwardly of the front wall 14 is rubber pad 67 for the purpose herein-after specified.

In the operation of the device steel balls are poured into hopper 17 to contact with and spill upon shiftable plate 21. When openings 23 in the two plates 20 and 21 are in register, as seen in Fig. 3, the lowermost balls 24 in hopper 17 will enter said openings 44 in tray 43. The thickness of plates 20 and 21 and the length of lugs 46 are predetermined, so that when openings 23 in the two plates 20 and 21 are in register it is possible for only two balls 24 to remain in a stacked relation within said openings 23 and seats 44, as is clearly seen in Fig. 3. It is noted that in that stacked position of said balls 24 only an upper portion of the body of the uppermost ball enters opening 23 in the stationary plate 20, major portion of the body thereof still remaining within opening 23 in said shiftable plate 21.

By virtue of the condition last hereinabove mentioned, when said plate 21 is shifted, the uppermost balls 24 remaining within the openings of said plate 21 will be caused to spring upwardly, and ultimately rest upon the body of stationary plate 20, thereby effectively preventing the balls from entering openings 23 in said stationary plate 20. The shifting movement of said shiftable plate 21 is brought about by imparting rocking movement to said shaft 35, arm 38 and bar 27, as was hereinabove described. When said shiftable plate 21 has been shifted to its inoperative position, illustrated in Fig. 4, the lowermost balls 24 that have theretofore passed through registering openings 23 in plates 20 and 21, are within seats 44 upon tray 43, ready to be withdrawn with said tray 43 when the latter is shifted through opening 22 forwardly of the box. That shifting of tray 43 is accomplished by manual grasping of the free ends of the vertical portion of angle member 47. Of course, when said tray 43 has been filled with balls 24, prior to the withdrawal of said tray 43 from the said box through opening 22, treadle 65 is stepped upon for bodily shifting of said tray 43 with balls reposing thereon in a downward direction in order to withdraw completely said balls from openings 23 in said stationary plate 20, position indicated by dotted lines in Fig. 4, for bringing the balls upon tray 43 out of the path of said stationary plate 20. Foot pressure upon treadle 65 is maintained until tray 43 is completely withdrawn from the box.

The body portion of plates 20 and 21 adjacent the upper end of each opening 23 is chamfered. This construction facilitates the uppermost balls 24 within openings 23 in said shiftable plate 21 to spring upwardly and away from the lowermost balls 24 already remaining upon tray 43 when a shifting movement is imparted to said shiftable plate 21 in order to bring its openings 23 out of register with openings 23 in the stationary plate 20.

In order to maintain said stationary plate 20 in position and to prevent its shifting an L-shaped insert 68, by one of its legs, is inserted within the front end of each side wall 15 and each end of the front wall 14, for preventing forward shifting

of said stationary plate 20. Said plate 20 is recessed at its ends adjacent the front edge thereof for accommodating one leg of said inserts 68. The other legs of said inserts 68 contact the outer faces of side walls 15 and are there rigidly and disengagably affixed. Shiftable plate 21 at its front corners is also suitably recessed to provide clearance past said inserts 68, in order that the latter may not interfere with the shifting movement of said plate 21.

It is noted that plates 20 and 21 and tray 43 are interchangeable with similar plates and tray of varying diameters of openings 23 and seats 44 but of diameters corresponding to any given size of balls 24 in order to accommodate various diameters, either larger or smaller, of balls 24. When inserts 68 have been disengaged from side walls 15 and withdrawn, stationary plate 20 may then be withdrawn and another one substituted in lieu thereof with openings 23 of a different diameter corresponding to the diameter of balls 24 to be deposited upon tray 43. Shiftable plate 21 may also be withdrawn from the box, upon first disconnecting pin 39 from bar 26. When plate 41 is disconnected on disengaging screw 42, bar 26 may be withdrawn from the box and through recess 28 when said shiftable plate 21 is shifted in a forward direction, that is forwardly of front wall 14.

Means are provided for agitating tray 43 and imparting rotary movement to balls 24 resting upon said tray 43 in order to expose the entire peripheries of said balls upon tray 43 to a visual inspection in order to determine whether or not the balls are otherwise perfect and do not have any flaws upon their faces.

That latter means includes a pair of channel guides 69, one coacting with each of said rollers 49. When tray 43 is within the box, and disposed below said stationary plate 20, with the vertical portion of angle member 47 in contact with the front wall 14, said rollers 49 are already within the adjacent ends of said channel guides 69, as is clearly seen in Figs. 1 and 2. As said tray 43 is shifted forwardly rollers 49 shift within said guides 69 during the forward shifting movement of said tray 43. Rubber pad 67 constitutes a support for said tray 43 during the shifting movement of the latter. As said tray 43 shifts upon said rubber pad 67, said balls 24, tending to partially extend through openings 44, as was hereinabove mentioned, contact with pad 67 thereby imparting to said balls 24 a rotary movement in one direction, that is longitudinally of said pad 67. This affords visual inspection of the balls upon tray 43 as the same is shifted upon pad 67 and as said balls 24 rotate due to the friction exerted thereon by said pad 67.

Pad 67 need not necessarily be made of rubber. A wooden board or a metallic sheet will give equally good results.

In order to impart to said balls 24 upon tray 43 rotary movement in several directions, that is along a plurality of their axes, said tray 43 must be agitated into a number of directions in order that said balls 24 may be viewed from a number of angles so that the entire peripheries of the balls may be subjected to inspection. To accomplish this purpose suitable guides are provided adjacent the opposite ends of said channel guides 69 which guide said rollers 49 in order to impart a suitable agitating movement to tray 43.

The guides for rollers 49, for the purpose of imparting an agitating movement to tray 43, when the same reposes upon rubber pad 67, include blocks 70, each of which has an L-shaped

edge, upon which a plurality of serrations 71 are made. Co-acting with each of said blocks 70 is plate 72, having an L-shaped recess, co-extensively with which a plurality of serrations 73 are made in the body portion of said plate 72, along said recess. The serrated edges in blocks 70 are in a spaced relation with the serrated edges in plate 72, as seen in Fig. 1, so that said blocks 70 in conjunction with spaced plates 72 define sinusoidal recesses 74. The horizontal portions of said recesses 74 are turned to the same direction, and by their free ends communicate with the ends of said channel guides 69.

When tray 43, with the vertical portion of angle member 47, blocks 48 and rollers 49 is extended forwardly, said rollers 49 will enter the horizontal portions of said recesses 74. Shifting of said rollers 49 along the horizontal portions of said recesses 74, until said rollers 49 come to the corners of said recesses 74, will impart an agitating movement to tray 43, generally along a horizontal line, with a jerking motion imparted to tray 43, and along vertical plane, as said rollers 49 strike serrations 71 and 73. This guiding movement will impart a rotary movement to balls 24 upon tray 43, generally upon a horizontal plane, that is transverse of pad 67. When said rollers 49 hit the vertical portions of said recesses 74 an agitating movement of tray 43, opposite of that hereinabove described, takes place. The vertical portions of said recesses 74 impart to balls 24 a general rotation longitudinally with relation to pad 67, with short lateral movement, due to rollers 49 clearing several serrations 71 and 73 in the vertical portions of said recesses 74.

Blocks 70 and plate 72 are affixed, by means of screws 75, to metallic inserts 76, which in turn are rigidly affixed to table 10 by means of screws 77.

The modified form of guides for rollers 49, for the purpose of imparting an agitating shifting movement to tray 43, is shown in Fig. 6. The modified form of said guides includes block 78, which is affixable to inserts 76 by means of screws passed through apertures 79. Block 78 has recess 80, which is open at one of its ends, along one edge of block 78, as at 81. Said open end 81 of recess 80 communicates with channel guide 69 for reception therewithin of roller 49. Recess 80 generally follows an oblique direction with relation to block 78. The body portion of said block 78 adjacent the sides of said recess 80 has alternate horizontal and vertical edges, for defining alternate horizontal passages 82 and vertical passages 83. By virtue of this construction of the guide, shown in Fig. 6, a general diagonal rotary movement to balls 24 upon tray 43 will be imparted, with relation to pad 67, with short alternate rotary movements, once transverse and then longitudinal with relation to pad 67, as said rollers 49 alternately pass along horizontal passages 82 and vertical passages 83 in recesses 80.

Whether the agitating movement to tray 43 is imparted by guides 70—72, or by guides 78, the ultimate function of either will be the same, because each pair of said guides will cause the rotary movement of balls 24 upon tray 43 in all possible directions so as to subject said balls to the visual inspection from all possible angles for detecting any flaws or imperfections upon the surface of the balls in order that such balls may be discarded.

As was noted, seats 44 in tray 43 are of sufficiently large diameter, permitting portions of balls 24 upon tray 43 to extend past the lower face 76 of tray 43, were said tray lifted. By virtue of

this arrangement, when tray 43 remains in contact by its lower face with rubber pad 67, the latter provides traction for the balls which are in contact with said pad 67.

Thus, when tray 43 is shifted upon the face of said rubber pad 67, the body portions of said tray 43 adjacent openings 44 guide balls 24 in their rotary movement upon pad 67.

From the hereinabove descriptions it will be apparent that the main object of openings 23 in both plates 20 and 21 is to deposit in unison a single layer of balls 24 upon tray 43 from hopper 17, when said openings 23 in the two plates are in register. Shifting of plate 21 in order to bring openings 23 in the two plates out of register, preparatory to the removal of tray 43 from the box, effectively bars the balls in hopper 17 from feeding through the two plates in the absence of tray 43 therebelow.

When guiding hopper 17 is loaded with some of the balls spilled upon shiftable plate 21 through the space defined by the lower end of said hopper 17 and said plate 21, it is often difficult to agitate said plate 21 through lever 30 and shaft 35 due to the weight of the balls within said hopper 17 pressing and weighing upon said plate 21. To obviate this difficulty I have devised a storing hopper from which balls may be shifted to said guiding hopper 17 in such smaller quantities at any given time as may be desired in order to render said plate 21 capable of shifting at all times.

Referring now more particularly to Figs. 8 and 9 there is shown storing hopper 84 capable of receiving and holding a large quantity of metallic balls. Inclined track 85, the rear end of which constitutes the bottom of said hopper 84, downwardly slants towards said guiding hopper 17. The rear wall of said guiding hopper 17 is cut away as at 86 for receiving in the resulting recess the front end of said track 85. A pair of wings 87, extending rearwardly of said hopper 17 from the side marginal body portions of the rear wall of said hopper 17 adjacent said recess 86. Said wings 87 may be integrally formed with the rear wall of guiding hopper 17, or they may be affixed to wall 13.

Said wings 87 maintain said track 85 in an operative connected position with relation to guiding hopper 17. The front end of said track 85 rests upon the horizontal body portion of the rear wall of said hopper 17 adjacent said recess 86. Said track 85 and said hopper 84 are supported upon table 10 in an elevated position by means of a plurality of standards 88 which are affixed to said table 10.

Affixed to the inner face of each side wall of storing hopper 84, and adjacent the front end thereof is U-shaped guide 89. Receivable within a pair of said guides 89 is plate 90 which defines the front wall of said storing hopper 84. Said plate 90 is frictionally held within said guides 89 and may be shifted in a vertical direction to or away from said track 85 for defining slot 91, through which the balls held in said storing hopper 84 may pass and roll downwardly upon said track 85 and into guiding hopper 17.

Co-acting with said plate 90 is gate 92, disposed forwardly of said plate 90 for the purpose of selectively opening or closing said slot 91 as said gate 92 is shifted either upwardly or downwardly. The front terminations of the side walls of said storing hopper 84 are turned inwardly for defining lips 93, which, coacting with guides 89 constitute guiding means for upright shifting of said gate 92.

Affixed to the upper end of said gate 92 is lug 94, with which arm 95 connects. Said arm 95 is pivotally supported upon post 96 which in turn is supported by and upon table 10. Said arm 95 extends from the central portion of said gate 92, at which said lug 94 is connected, so that said arm is directed in a diagonal direction with relation to track 85, and extends towards said post 96, which is at a side of said track 85. Some distance past said post 96 said arm 95 is bent so that its outer free end remains laterally of the box defined by walls 13, 14 and 15, and remains in a parallel relation with the side walls 15 of said box, and is disposed thereabove. The free end of said arm 95 carries handle 97 by means of which said arm 95 may be angularly shifted upon post 96, in either direction for the purpose of raising or lowering said gate 92.

Coacting with said track 85, and extending from each side margin thereof is wall 98, which in cooperation with said track 85 provide a chute for the balls from storing hopper 84 to guiding hopper 17. Said track 85 is positioned within wings 87 with said side walls 98 in contact therewith. Both said side walls 98 and said wings 87 are slotted for accommodating closure 99 which is guided therewithin for upright sliding movement.

When said gate 92 and said closure 99 are both open, that is in a raised position above track 85, the balls stored in hopper 84 will be permitted to roll upon track 85 and into guiding hopper 17. The quantity of balls passing into said guiding hopper 17 at any given time may be regulated by the sizes of the openings made by the raising of gate 92 and closure 99.

By virtue of said storing hopper 84, gate 92 and closure 99 the quantity of balls passing into said guiding hopper 17 and upon shiftable plate 21, may be regulated, and such quantity of balls may be caused to drop upon said shiftable plate 21 as may be required in any given time, thereby eliminating an undue load of balls upon said shiftable plate 21 which may prevent said shiftable plate 21 to shift for proper distribution of balls thereon and into openings 23.

While there is described herein a preferred embodiment of the present invention, it is nevertheless to be understood that minor changes may be made therein without departing from the spirit and scope of the invention as claimed.

What I claim as new is:

1. A device for revolving steel balls to facilitate a visual inspection thereof comprising a tray, said tray being provided with a plurality of openings within which the individual balls are receivable, said openings being of sufficiently large diameters for normally permitting portions of the peripheries of the balls to extend through said tray, a traction support normally in contact with the lower face of said tray for effecting contact of the balls extending through said openings with said traction support, a guided member carried by said tray, and a block in a stationary relation with said traction support, said block being provided with a recess of a sinuous formation, said guided member being receivable within said recess, on shifting said guided member within said recess said tray being capable of shifting upon said traction support in a number of directions as predetermined by the formation of said recess for imparting to the balls a revolving movement within said opening along a plurality of their axes.

2. A device of the class described comprising a hopper, said hopper being adapted to receive a

11

plurality of metallic balls, a stationary plate disposed below said hopper, a shiftable plate in association with said stationary plate, both of said plates being provided with a plurality of openings, means for shifting said shiftable plate for bringing the openings in the two plates into or out of register, and a removable tray disposed below said plates, said tray being provided with a plurality of openings of diameters smaller than the diameters of the balls, said openings in said tray being in an alignment with the openings in the two plates when said tray remains in an operative position with relation to said plates, when the openings in the two plates are in register the balls passing from said hopper through the registered openings in the two plates for depositing within said openings in said tray, the body portions of said tray adjacent said openings in said tray defining seats for supporting the individual balls deposited upon said tray.

3. A metallic ball handling machine comprising a guiding hopper, a shiftable plate disposed therebelow, a stationary plate disposed below said shiftable plate, said plates being provided with openings, said openings being adapted to selectively come into or out of register on shifting said shiftable plate, means supported on said machine below said plates to receive and hold individual balls in spaced relation when said openings are in register, a storing hopper adapted to receive a quantity of balls, and means in association with said storing hopper for passing therefrom a predetermined quantity of balls into said guiding hopper and upon said shiftable plate.

4. A metallic ball handling machine comprising a guiding hopper, a shiftable plate disposed therebelow, a stationary plate disposed below said shiftable plate, said plates being provided with openings, said openings being adapted to selectively come into or out of register on shifting said shiftable plate, means supported on said machine below said plates to receive and hold individual balls in spaced relation when said openings are in register, a storing hopper adapted to receive a quantity of balls, and means in association with said storing hopper for passing therefrom a predetermined quantity of balls into said guiding hopper and upon said shiftable plate, said means including an inclined track connecting said storing hopper with said guiding hopper, and a shiftable gate capable of releasing a quantity of balls from said storing hopper to said track.

5. A metallic ball handling machine comprising a guiding hopper, a shiftable plate disposed therebelow, a stationary plate disposed below said shiftable plate, said plates being provided with openings, said openings being adapted to selectively come into or out of register on shifting said shiftable plate, means supported on said machine below said plates to receive and hold individual balls in spaced relation when said openings are in register, a storing hopper adapted to receive a quantity of balls, an inclined track connecting said storing hopper with said guiding hopper, and a shiftable wall in said storing hopper, said wall defining an adjustable slot in said hopper in communication with said track for regulating the quantity of balls passing from said storing hopper into said track.

6. A metallic ball handling machine comprising a guiding hopper, a shiftable plate disposed therebelow, a stationary plate disposed below said shiftable plate, said plates being provided with

12

openings, said openings being adapted to selectively come into or out of register on shifting said shiftable plate, means supported on said machine below said plates to receive and hold individual balls in spaced relation when said openings are in register, a storing hopper adapted to receive a quantity of balls, an inclined track connecting said storing hopper with said guiding hopper, a shiftable wall in said storing hopper, said wall defining an adjustable slot in said hopper in communication with said track for regulating the quantity of balls passing from said storing hopper into said track, and a shiftable gate in the path of said slot for intermittently closing and opening said slot.

7. A device for revolving steel balls to facilitate a visual inspection thereof comprising a tray, said tray being provided with a plurality of openings within which the individual balls are receivable, and a traction support normally in contact with the lower face of said tray, said openings being of sufficiently large diameters so as to effect the contact of the balls with said traction support, when a shifting movement is imparted to said tray the balls being adapted to revolve in said openings due to the friction engendered by said traction support upon the balls.

8. A device for revolving steel balls to facilitate a visual inspection thereof comprising a tray, said tray being provided with a plurality of openings within which the individual balls are receivable, a traction support normally in contact with the lower face of said tray, said openings being of sufficiently large diameters so as to effect the contact of the balls with said traction support, and means for shifting said tray upon said traction support in a number of predetermined directions for imparting to the balls a revolving movement within said openings along a plurality of their axes.

9. A device for revolving steel balls to facilitate a visual inspection thereof comprising a tray, said tray being provided with a plurality of openings within which the individual balls are receivable, said openings being of sufficiently large diameters for normally permitting portions of the peripheries of the balls to extend through said tray, a traction support normally in contact with the lower face of said tray for effecting contact of the balls extending through said openings with said traction support, means forming a surface adjacent the tray, and means secured to said tray coacting with said surface to effect a revolving movement of said balls along a plurality of their axes as said tray is moved relative to said traction support.
